UNITED STATES PATENT OFFICE

CHARLES TUTEUR, OF CHICAGO, ILLINOIS

DESIGN FOR A DOORSTOP

Application filed July 23, 1930. Serial No. 36,449. Term of patent 3½ years.

To all whom it may concern:

Be it known that I, CHARLES TUTEUR, a citizen of the United States, and resident of Chicago, in the county of Cook and State of Illinois, have invented a new, original, and ornamental Design for a Doorstop, of which the following is a specification, reference being had to the accompanying drawing, forming a part thereof.

The figure in the drawing is a view in perspective of a doorstop showing my new design, the opposite side being substantially the same.

I claim:

The ornamental design for a door stop substantially as shown and described.

Signed at Chicago, in the county of Cook and State of Illinois, this 18th day of July, A. D. 1930.

CHARLES TUTEUR.
